UNITED STATES PATENT OFFICE.

CHARLES MIDDLEBROOK, OF BROMLEY, ENGLAND.

COIN-OPERATED MACHINE.

SPECIFICATION forming part of Letters Patent No. 453,496, dated June 2, 1891.

Application filed July 10, 1890. Serial No. 358,341. (No model.)

To all whom it may concern:

Be it known that I, CHARLES MIDDLEBROOK, a subject of the Queen of Great Britain and Ireland, residing at Bromley, in the county of 5 Middlesex, England, have invented new or Improved Apparatus for Receiving Coin or an Equivalent and Supplying Gas in Exchange Therefor, of which the following is a specification.

10 This invention relates to new or improved apparatus for receiving coin or an equivalent, such as any suitable pieces of metal, (hereinafter included in the expression "coin,") and supplying gas in exchange therefor, and particularly to that class of apparatus for these 15 purposes in which locking and releasing mechanism is so combined with a gas-meter of any suitable construction that by the introduction of a coin the meter will be released 20 and allowed to deliver a given quantity or measurement of gas, and then will be automatically arrested and locked, so as to cease delivery until again released by another coin, and so on.

25 In my apparatus there is combined with the gas-meter mechanism of novel construction, as hereinafter described, which mechanism comprises a lever so arranged in relation to a coin chute or passage and to a device or 30 part operated by the meter when the latter is delivering gas that the lever, when not depressed by a coin, forms a stop and prevents the working of the meter; but when a coin is introduced so as to depress one end of said 35 lever the before-mentioned device is no longer obstructed, and the meter being thus released goes on delivering gas until the quantity of 40 gas to be supplied in exchange for the coin or coins that was or were on the lever has been supplied, whereupon said coin or the last one, if there had been several, will be caused to pass into a coin-receptacle, and the lever will assume a position in which it 45 will again lock the meter until another coin or coins is or are inserted into the machine, and so on; and in order that others skilled in the art may be enabled to make and use my invention, I proceed to explain the same more fully by reference to the accompanying illustrations.

50 In the drawings, Figure 1 shows in side elevation an apparatus according to this inven-

tion for receiving coin or equivalent and supplying gas in exchange therefor, certain parts of the apparatus being removed for the sake 55 of clearness. Fig. 2 is a plan of the apparatus with covers and coin-chute removed. Fig. 3 is a vertical section of part of the apparatus on the line $x-x$, Fig. 1. Fig. 4 is a separate view of the coin-lever in side elevation. Fig. 5 is an end elevation of the apparatus.

In the example shown the gas-meter A is a dry one provided with measuring-bellows that oscillate two vertical spindles 1 1^a, upon which 65 are fixed lever-arms 2 2^a, respectively, by which motion is transmitted from the spindles to the worm-wheel 3 on the shaft 4 of the counting mechanism 5 through links 6 and 7, pin 8, adjustable nut 9, crank-arm 10, shaft 70 11, and worm 12. 13 is the inlet for gas, and 14 the outlet. The construction and operation of these parts are well known, and of themselves form no part of this invention. The coin-receiving mechanism for use with 75 this meter comprises an inclined coin-chute 15, below which is a coin-lever 16, pivoted at 17. One end of this lever is arranged below the lower open end of the chute, and the other end, which is weighted, is recessed at 18 to 80 form a stop for an arm 19 when the lever 16 is in the position shown in Fig. 1. The arm 19 is fixed to the spindle 1 and is oscillated thereby when the meter is in action; but when its motion is arrested it stops the working 85 of the meter. In lieu of the arm 19, any other suitable device or part operated by the meter when the same is delivering gas can be used.

20 is a starting-lever so formed and arranged that its lower end will be caused to exert pressure through a coin B to depress the lever 16 and disengage it from the arm 19 should this be pressed so tightly against the lever by the pressure of the gas acting upon 90 the internal mechanism of the meter when the meter is locked as not to be released by the weight of the coin alone. As will be seen, this starting-lever 20 is so arranged that it can only operate the coin-lever 16 when a coin 95 is located between them.

21 is a chute through which a coin passes into a suitable receptacle after it has unlocked the meter and kept it unlocked while

the equivalent quantity of gas is being delivered.

22 is a projection, hereinafter called a "divider," arranged within the chute 15 and between this chute and the chute 21.

23 is a projection, part, or cam, hereinafter referred to as a "cam," carried by a toothed wheel 24, which is rotated from the worm 12 by a worm-wheel 25, shaft 25^a, pinion 26, toothed wheel 27, shaft 28, and toothed wheel 29.

30 is a fixed plate for supporting the outer ends of the shafts carrying the toothed wheels 24, 26, 27, and 29.

21^a is an abutment in front of which the lower end of the lever 16 moves when being depressed and against which the coin rests so as to maintain the lever in its depressed position until it is raised by the cam 23, as hereinafter described.

20 In lieu of the cam 23 any other suitable device operated by the meter and arranged to act against the coin-lever in opposition to the weight of the coin thereon, as hereinafter described, can be used. Such a device is included in the generic expression "cam," hereinafter used.

The operation of the apparatus is as follows: A coin B—say a penny—dropped into the chute 15 through the money-slot at 15^a, Fig. 1, will roll down the chute and onto the lower end of the coin-lever 16. The weight of the coin, aided by pressure exerted through the coin by the starting-lever 20, will depress the lower end of the lever onto the top of the cam 23, thereby raising the other end of the lever sufficiently to release the arm 19 and unlock the meter. On the further falling of the cam-lever 16, as the cam 23 rotates from under it, the coin upon it will fall with it, but does not pass out of contact with the divider 22 until the extreme lower end of the lever is at such a distance below the top edge of the coin stop or abutment 21^a that this stop or abutment will prevent the coin, when it rolls under the divider, from passing into the chute 21. The meter will then supply gas until the lower end of the lever 16 is partly raised by the cam 23 assuming its uppermost position, at which time the coin will be raised sufficiently by the lever to clear the stop or abutment 21^a and roll into the chute 21.

One coin only can pass into the chute 21 at a time, and should there be more than one in the money-slot the first coin will pass under the divider 22 and the second coin will, on the partial rising of the lever 16, be separated from the first by the divider 22, the first coin being on the side of the divider nearest the chute 21, while the next coin will be on the opposite side. The lever 16 is so weighted or pivoted that when no coin rests upon its lower end this end will rise and the upper end will fall sufficiently to come into the path of the arm 19, and so stop the meter; but so long as there is a coin present to act upon the lower end of the lever 16 neither the weight of the upper end of the lever or the cam 23 will cause

the lever to assume a position in which it will lock the arm 19 and stop the delivery of gas. The gearing for driving the cam 23 from the worm 12 is so proportioned that the cam makes one complete revolution while the quantity of gas to be delivered in exchange for a coin is passing through the meter.

At one portion of its length the outer wall 75 of the coin-chute 15 is formed with an opening 31, Fig. 3, and at this part the bottom of the chute on which a coin rolls is slightly rounded off or beveled, as shown at 32, so that a coin passing down the chute has a tendency to slip sidewise through the opening before reaching the lower end of the coin-lever 16. The width of the chute 15 and the depth of the opening 31 are so proportioned that a penny will not slip out, being too thick, but 85 a half-penny or less coin will do so and fall through the chute 33, so that it cannot be used to start the meter. To assist this action the side walls of the chute 15 are inclined to the vertical, as shown in Fig. 3, and the inner 90 wall is formed with an opening 31^a, that will allow a coin smaller than the proper one to become inclined sufficiently to fall through the opening 31.

The starting-lever 20 need only be used 95 after the meter has been at rest to assist the first coin resting on the lever 16 to release this lever from the arm 19. The starting-lever 20 can be moved by means of the small knob 20^a.

34 is a cover that incloses the coin-receiving apparatus, excepting the coin-slot at 15^a and the upper end of the starting-lever 20.

What I claim is—

1. In an apparatus for receiving coin or an equivalent and supplying gas in exchange therefor, the combination, with a meter, of coin-receiving mechanism comprising a coin-lever arranged to serve when not depressed by a coin as a stop to the meter, a coin-stop adapted to prevent a coin from prematurely leaving said lever, a cam actuated by the said meter and arranged to act at the required time upon said coin-lever, and a divider arranged above said lever, substantially as hereinabove described, for the purposes specified.

2. In an apparatus for receiving coin or an equivalent and supplying gas in exchange therefor, the combination, with a meter, of coin-receiving mechanism comprising a coin-lever arranged to be acted upon by a coin or coins and capable of forming a stop to a device or part operated by said meter when it is delivering gas, a cam also actuated by said meter and arranged to act at the required time upon said lever in opposition to the weight of coin thereon, and a starting-lever adapted to be operated from the exterior of the apparatus and to then exert pressure upon the coin-lever if there be a suitable coin between the two, substantially as herein described, for the purpose specified.

3. In an apparatus for receiving coin or an equivalent and supplying gas in exchange

therefor, the combination, with a meter, of coin-receiving mechanism comprising a coin-chute, a coin-operated device capable of forming a stop to a device or part worked by said meter 5 when delivering gas, a cam also actuated by said meter and arranged to act at the required time upon said coin-operated device in opposition to the weight of coin thereon, a divider arranged opposite said coin-lever and within 10 said chute, and a second chute at the side of said divider opposite to said first chute, substantially as herein described, for the purpose specified.

4. In an apparatus for receiving coin or an equivalent and supplying gas in exchange therefor, the combination, with a meter, of coin-receiving mechanism comprising a coin-chute, a coin-operated device capable of forming a stop to a device or part worked by said meter 15 when delivering gas, a divider arranged within said chute and opposite said coin-lever, a second chute at the inner side of said divider, an abutment arranged to retain the coin on said device when the same is depressed, and a 20 cam also actuated by said meter and adapted to move said device into a position to discharge a coin thereon into the second chute, but not to stop said meter, substantially as herein described, for the purpose specified.

5. In an apparatus for receiving coin or an equivalent and supplying gas in exchange therefor, the combination, with a meter, of coin-receiving mechanism comprising a coin-chute with open slot for insertion of coin, a divider 35 arranged at the inner end of said chute, a second coin-chute at the opposite side of said divider, a coin-lever having one end arranged below the inner end of the first coin-chute and capable of forming a stop to a device or part 40 worked by said meter when delivering gas, and an abutment, in front of which the one end of said coin-lever moves when depressed and against which a coin-supported by the depressed end of said lever can rest, substantially as herein described.

6. In an apparatus for receiving coin or an equivalent and supplying gas in exchange therefor, the combination, with a meter having a movable arm 19, of coin-receiving mechan-

ism comprising an inclined coin-chute 15, a 50 coin-lever 16, having one arm arranged below the inner end of said coin-chute and the other arm recessed to act as a stop to said movable arm 19, a divider arranged within said chute and above said lever, a second coin-chute 21 55 at the inner side of said divider, an abutment 21^a for a coin when in its lowered position, and a cam 23, actuated by said meter when delivering gas, substantially as herein described, for the purposes set forth.

7. In an apparatus for receiving coin or an equivalent and supplying gas in exchange therefor, the combination, with a meter having a movable arm 19, of coin-receiving mechanism comprising an inclined coin-chute 15, a 65 coin-lever 16, having one arm arranged below the inner end of said coin-chute and the other arm recessed to act as a stop to said movable arm 19, a divider arranged within said chute and above said lever, a second coin-chute 21 70 at the inner side of said divider, a cam 23, actuated by said meter when delivering gas, and a starting-lever 20, arranged above said coin-chute 15 and capable of being operated from the exterior of the apparatus and of depressing 75 the lower end of said coin-lever 16 through a coin carried thereby, substantially as herein described, for the purpose specified.

8. In an apparatus for receiving coin or an equivalent and supplying gas in exchange 80 therefor, the combination, with a meter, of coin-receiving mechanism constructed with an inclined coin-chute 15, having its side walls inclined to a vertical plane and formed with openings 31 31^a, and the portion of its bottom 85 adjacent to the opening 31 rounded off or beveled sidewise, substantially as herein described, for the purpose specified.

In testimony whereof I have signed my name to this specification, in the presence of 90 two subscribing witnesses.

CHARLES MIDDLEBROOK.
